(57) CLAIM

I claim the ornamental design for an outsole for a shoe, as shown and described.

DESCRIPTION

FIG. 1 is a bottom view of an outsole for a shoe showing my new design;

FIG. 2 is a right side view thereof;

FIG. 3 is a left side view thereof;

FIG. 4 is a front view thereof; and

FIG. 5 is a rear view thereof

FIG. 6 is a perspective view of the detail of area 6 in FIG. 1; and,

FIG. 7 is an enlarged fragmentary view showing the details of the heel.

The broken lines showing a shoe upper in all of the views, except FIGS. 1 & 6, illustrate the portion of the design that forms no part of the claim.
